UNITED STATES PATENT OFFICE

2,554,067

PIPE COATING MACHINE

Oliver R. Smith, Fort Worth, Tex.

Application October 9, 1948, Serial No. 53,713

2 Claims. (Cl. 91—43)

1

This invention relates to a pipe coating machine.

An object of the invention is to provide equipment of the character described which is used for applying a coating to pipe, particularly pipe lines in reconditioning the same.

It is another object of the present invention to provide a portable tank mounted on a tractor, preferably of the Caterpillar type, with means for heating the pipe coating material in the tank, for agitating or circulating said liquid material about the heating coils with means for delivering the coating material to the point of utilization and with means for moving the entire equipment alongside the pipe line being treated.

The invention also embodies means for suspending the pipe coating machine from the equipment and for adjusting it with relation to the pipe being coated so that the coating machine will at all times be maintained in correct operating position relative to the pipe.

Other objects and advantages will be apparent from the following specification which is illustrated by the accompanying drawings, wherein:

Figure 1 is a plan view of the conditioning machine shown in its relation to the pipe line.

Figure 2 is a side elevation thereof, and

Figure 3 is a front elevation.

Referring now more particularly to the drawings wherein like numerals of reference designate the same parts in each of the figures, the numeral 1 designates the supporting frame as a whole which, as illustrated is mounted on any conventional type of Caterpillar tractor 2.

Extending forwardly from the frame there is a bracket 3 and a motor 4 is supported at its rear and forward ends, respectively, by the forward end of the frame and by said bracket.

Spaced rearwardly of the motor and supported on the frame there is a tank 5 for heating the pipe coating liquid. This tank is closed but its top is provided with inlet openings normally maintained closed by shutters, as 6.

The tank is equipped with inside heating coils, as 7, 7. These coils extend substantially throughout the length of the tank and each terminates, at one end, in an upwardly directed outlet flue 8 and at its other end terminates in a furnace 9 at the rear end of the tractor frame. The coils are spaced apart at the bottom of the tank.

The furnace 9 is equipped with suitable burners 10, 10 which are supplied with fuel from a fuel tank 11 located above them and carried by the rear end of the tank 5.

A feed line 12 leads from the fuel tank 11 to 55 around the pipe to be coated.

2

the burners and is controlled by suitable valves, as 13. The furnace is substantially closed so that the heat generated therein passes through the coils 7, 7 which constitute flues for the furnace and the coating liquid is thereby heated.

Arranged midway between the coils 7 and extending longitudinally of the tank 5 there is a shaft 14 which is mounted for rotation in suitable bearings provided for the purpose and this shaft has longitudinally extended vanes 15 disposed therearound and spaced apart longitudinally of the shaft. The forward end of the shaft has a sprocket wheel 16 fixed thereon and there is a sprocket chain 17 which operates over said sprocket wheel to drive the shaft 14, said sprocket chain 17 being driven from the driving shaft of the motor 4. The motor driving shaft may be clutched with, and declutched from, the chain 17 by any conventional clutch mechanism.

When the shaft 14 is connected with its driving mechanism it will be rotated and the vanes 15 will effectively circulate the coating liquid about the heating coils.

Supported by the tractor framework and embracing the tank 5 there are the upstanding inverted front and rear U-frames 18 and 19 and mounted to rotate between them, at one side of the tank, there is a cable winding drum 20 which is operatively connected with the motor 4 in the conventional manner through the driving chain 21 and driving shaft 22 connected therewith.

At the side of the tractor opposite the drum 20 there is a boom 23 whose side arms are pivotally connected, at one end, to the lower ends of the U-frames 18, 19. The side arms of the boom 23 converge and are united at their free ends and carry a pulley 24. The boom may be manipulated by means of a cable 25 one end of which is connected to the free end of the boom, said cable 40 being wound about the drum 20 to be manipulated thereby. The drum 20 is operatively connected with the motor 4, as hereinbefore stated, said operative connections including a transmission mechanism 26 whereby the speed of the drum may be regulated and controlled.

There is a cable 27 which operates over the pulley 24 and one end of which is suitably connected to the tractor frame or to a manipulating winch provided for the purpose, such as 27a.

The other end of this cable carries a hook 28, or similar connecting means whereby it may be connected to the bail of a conventional type of pipe coating machine indicated generally by the numeral 29 and which is designed to travel along

Leading from the bottom of the tank and connected into the coating machine there is a delivery line 30 through which the coating material may be delivered to the coating machine as required and by it to the pipe to be coated.

In use the tractor moves alongside the elevated pipe line to be reconditioned with the coating machine 29 disposed around said line and swung from the boom 23. The coating material will be fed through the line 30 and the flow of said coating material may be controlled by a control valve 31 as illustrated in Figure 1. The coating operation may be continuous as additional coating material may be supplied, from time to time, to the tank 5 through the inlet openings which are normally closed by the shutters 6.

Of course pipe of any kind may be coated with the machine if desired and may be moved through the pipe coating machine 29 while the tractor is stationary.

The drawings and description are illustrative merely while the broad principle of the invention will be defined by the appended claims.

What I claim is:

1. In apparatus of the character described, in combination, a frame adapted to be mounted on a self-propelled tractor, a tank for heating pipe coating liquid supported on the frame, a furnace operatively connected to said tank mounted on said frame, a heating coil in said tank having one end terminating in an outlet flue and the other end terminating in said furnace, a fuel reservoir on the tank, a shaft arranged longitudinally in the tank and mounted for rotation therein, agitating means disposed around the shaft, driving means connected to the shaft to circulate the coating liquid about the heating coils, upstanding U-frames mounted on the frame and extending over said tank, a cable winding drum mounted to rotate between said U-frames at one side of the vehicle, converging side arms pivotally connected, at their lower ends, to said U-frames at the other side of the vehicle, a pulley carried on

the united ends of said arms, a cable wound about the drum and arranged to operate over the pulley, means secured to the free end of said cable to be connected to a pipe coating machine, a delivery line leading from the tank and connected into the coating machine to deliver the liquid to the coating machine.

2. In apparatus of the character described, in combination, a frame adapted to be mounted on a self-propelled vehicle, a tank for pipe coating liquid supported on the frame, upstanding U-frames connected at their ends to said frame at opposite sides of the vehicle and extending over the tank, cable winding mechanism mounted to rotate between said U-frames at one side of the vehicle, converging side arms united at their upper ends and pivotally connected at their lower ends to said U-frames at the other side of the vehicle, a pulley carried on the united ends of said arms, a cable wound on said winding mechanism and passing over said pulley, means secured to the free end of the cable to be connected to a pipe coating machine, cable means operatively connected to said winding mechanism and to said arms for raising and lowering said arms, and delivery line leading from the tank and connected into the coating machine to deliver the liquid to the coating machine.

OLIVER R. SMITH.
